RADIATOR HEADER WITH FLOATING TUBE
SHEET

Floyd J. Sibley, Detroit, Mich.

Application December 29, 1937, Serial No. 182,211

6 Claims. (Cl. 257—154)

My invention pertains to a radiator header with a floating tube sheet and to a method of assembling and balancing the same.

In the use of heat exchanger apparatus such as radiators, air conditioning and cooling units, and similar apparatus, considerable maintenance trouble is caused by the ends of the heat exchanger tubes pulling loose from the headers. This is caused by the circulated air blowing more directly against some of the tubes which are thereby cooled or heated more than the other tubes thus causing unequal expansion and/or contraction of the tubes. This maintenance difficulty occurs irrespective of whether the headers are joined only by the heat exchanger tubes or also by rigid structural members.

It is accordingly an object of my invention to provide an improved method of balancing a radiator header comprising heat exchanger tubes and a flexible tube sheet which consists in floating the atmospheric side of the tube sheet against a body of spongy material which serves as a balancing medium for supporting the tube sheet while permitting reverse movements of different portions thereof in accordance with the relative contraction or expansion of the different heat exchanger tubes.

It is also an object of my invention to provide a balanced radiator header comprising a plurality of heat exchanger tubes, a flexible tube sheet for receiving an end of each tube, a header casing secured around the edges of the tube sheet for conducting fluid for the tubes, outside cover means disposed on the atmosphere side of the tube sheet for slidably supporting the tubes and also for enclosing a cavity to hold a balancing material, a port in said cover for injecting a body of spongy balancing material into said cavity between the cover and the tube sheet to float the latter in balanced relation.

It is a further object of my invention to provide a header having an abutment member rigidly secured in the header casing for engaging in supporting relation against the flexible tube sheet while the spongy fluid is being injected or packed into the cavity and adapted to be spaced from the tube sheet a predetermined distance after the cavity has been filled.

Further objects and advantages are within the scope of my invention such as relate to the arrangement, operation and function of the related elements of the structure, to various details of construction and to combinations of parts, elements, per se, and to economies of manufacture and numerous other advantages, as will be ap-

parent from a consideration of the specification in conjunction with the drawing disclosing a form of my invention, which may be preferred, in which:

Fig. 1 is a plan view of the improved radiator header partially broken away, and the internal construction being shown by the dotted lines; and

Fig. 2 is a side elevational view thereof partially broken away and sectioned to show the internal construction and the cooperative relation of the elements therein disposed.

Referring more specifically to the figures of the drawing, my improved radiator header comprises a tube sheet 1 of a suitable gauge of sheet material to provide a flexible diaphragm like member. The tube sheet 1 may be made of any suitable sheet metal such as steel, bronze, iron or the like selected according to the pressure, temperature and chemical conditions of its exposure, as will be understood. The tube sheet 1 is apertured and provided with nipples 3 for receiving one end of each of a plurality of spaced heat exchanger tubes 5. The edges of the nipples 3 are turned into the ends of the tubes 5 and flared to secure the tubes in hermetically sealed relation in the tube sheet. This operation may be accomplished in any suitable manner, as will be understood, but I prefer to perform this operation in the manner disclosed and claimed in my copending patent application Serial No. 182,212 filed concurrently herewith.

The heater exchanger tubes 5, which are made of copper or any other metal having a suitable thermal conductivity, in accordance with the usual practice, extend in spaced parallel relation for connection at the opposite ends with a suitable header which may be any conventional rigid construction (not shown). As one of my improved balanced headers is sufficient to permit relatively free expansion and contraction of the heat exchanger tubes, it is only necessary to provide my improved header at one end of a radiator to entirely eliminate the maintenance troubles usually caused by the stresses set up by the unequal expansion and contraction of the heat exchanger tubes.

To provide for conducting a heat emitting or absorbing fluid to or from the heat exchanger tubes 5, a header casing 7 is provided which is of substantially dish shaped conformation having a flange 9 projecting laterally around its open edge for securing upon the peripheral edges of the tube sheet 1. A pipe fitting 11, which opens from the closed side of the header casing, is in-

ternally threaded for convenient connection with a pipe 12 supply line.

To support the flexible tube sheet 1 and prevent excessive inward distortion thereof, I provide an abutment member 13 which may be of any suitable conformation having spaced open portions 14 fitting around the nipples 3 and having closed portions disposed therebetween. For this purpose I preferably utilize a heavy plate 10 which is suitably apertured to fit over the nipples. The abutment plate 13 is secured, as by welding 15 around inside the open edge of the header casing 7 substantially flush with the laterally projecting flange 9.

15 Spaced from the outside, or the atmospheric pressure side, of the flexible tube sheet 1, I provide an outside cover 16 which has suitable apertures for passing the tubes 5 therethrough in snug sliding relation. The cover 16 has an offset 20 flange 17 for fitting on the edges of the tube sheet 1 for holding the cover in spaced relation from the tube sheet and defining a cavity 19 therebetween for receiving a balancing medium 20. An injection passage 21 extends through a 25 lug 23 projecting from one end of the cover 16 for connecting from the cavity 19.

The header casing 7 and the outside cover 16 may be cast of any suitable metal of a suitable thickness and weight according to the conditions 30 of operation to which they will be exposed such as pressure, temperature, corrosion and the like.

The header casing 7 and the outside cover 16 are secured to opposite sides of the tube sheet 1 by screws 24 passing through the edges of the 35 tube sheet and the flanges 9 and 17 which are thereby clamped on opposite sides thereof. A yieldable gasket 25 is disposed between the flange 9 of the radiator casing and the tube sheet 1 to conveniently provide a tight hermetically sealed 40 joint therebetween. The gasket 25 is made of any suitable material selected according to the conditions of operation to which it is to be exposed, as will be understood.

The thickness of the gasket 25 is particularly 45 selected to space the abutment member 13 a predetermined distance from the inside surface of the tube sheet 1 such that the tube sheet can flex freely under normal operating conditions, but it is prevented from collapsing inward under 50 abnormal conditions. Such an abnormal condition might be caused for example if in a heating system the steam is shut off and a dirty or sticky air vent valve would not permit air replacing the condensing stream.

55 When my radiator header has been assembled, I inject a balancing medium 20 such as graphite, into the cavity 19 to a pressure substantially equal to the operating pressure in the header casing, and the passage is then closed in any suitable 60 manner, as by a plug, to retain the balancing fluid. The graphite is preferably introduced in its dry condition. Also for low pressure work, and various other conditions, a piece of rubber or cork may be placed in the cavity for a balancing 65 medium.

In operation in heating or cooling systems, the 70 pressure on the flexible, diaphragm-like, tube sheet 1 from the heating or cooling medium in the header casing is substantially balanced by the pressure of the spongy balancing fluid in the cavity 19 on the outside of the tube sheet. In such 75 systems air is blown across the heat exchanger tubes to conduct heat from or to the tubes, and this results in the tubes which are directly exposed to the air blast being cooled, or heated,

more than the less exposed tubes. This phenomenon causes unequal expansion and contraction of the tubes setting up stresses which loosen the ends of the tubes causing leaks in the headers. This detrimental effect occurs irrespective of whether the headers are connected by rigid structural members or only through the tubes.

In accordance with my invention the unequal expansion and contraction of the heat exchanger tubes 5 cannot injure the radiator because as 10 some tubes expand they push the adjacent portion of the tube sheet 1 inwardly toward the abutment member 13, while at the same time other tubes of the radiator which have contracted, pull the tube sheet outwardly toward the 15 cover 16.

In this operation the spongy balancing material in the cavity 19 merely shifts from one part of the cavity to another thus continuously floating the tube sheet 1 and balancing it against the 20 pressure in the header casing. Hence, the flexible tube sheet 1 substantially floats upon the spongy material in the cavity 19 in balanced relation. My improved balanced header can be conveniently installed on any conventional radiator. 25

In order to properly assemble and balance my improved radiator header, I first secure the radiator casing 7 and the cover 16 to the opposite sides of the tube sheet 1 omitting the gasket. The spongy balancing material is now introduced into 30 the cavity 19 in the cover to provide a balancing pressure substantially equal to the operating pressure that will be used in the header casing. During this operation, the abutment plate 13 is disposed directly adjacent the flexible tube sheet 35 1 for rigidly supporting it against the pressure of the spongy balancing fluid. The header casing 7 is then released and the gasket 25 is inserted between it and the flue sheet. The header casing 7 is then clamped firmly down upon the gasket in 40 hermetically sealed relation and the header is prepared for balanced operation with the abutment plate 13 properly spaced to permit free flexing of the tube sheet 1.

It is apparent that within the scope of my invention, modifications and different arrangements may be made other than herein disclosed, and the present disclosure is illustrative merely, the invention comprehending all variations thereof. 50

I claim:

1. The method of balancing a radiator header comprising heat exchanger tubes, a flexible tube sheet, a header casing, an abutment member therein, and a cavity enclosing outside cover plate 55 apertured for sliding on said tubes which consists in; securing said header casing and said outside cover plate to opposite sides of said tube sheet with said abutment member abutting said tube sheet, forcing a balancing material into the cavity 60 in the cover plate adjacent the outside of said tube sheet, releasing the header casing from the tube sheet, inserting a gasket between the header casing and the tube sheet, and securing the header casing on the gasket and the tube sheet 65 with the abutment member spaced apart therefrom.

2. In combination in a balanced radiator header, a plurality of spaced heat exchanger tubes, a flexible tube sheet for receiving an end 70 of each tube, a header casing adjacent one side of said tube sheet and secured around the edges thereof for conducting fluid for the tubes, cover means disposed adjacent the other side of the tube sheet for enclosing a cavity, and a balancing 75

- material in said cavity to float said tube sheet in balanced relation thereon.
3. In combination in a radiator header, a plurality of spaced heat exchanger tubes, a tube sheet having tube receiving apertures for receiving an end of each tube in hermetically sealed relation, said tube sheet comprising a flexible diaphragm-like member which is freely yieldable to permit unequal contraction and expansion of said heat exchanger tubes, a header casing having a laterally projecting flange secured around the edges of said tube sheet for providing conductive connection through said heat exchanger tubes, a port in said header casing for transmitting fluid therethrough, an abutment plate rigidly secured in said header casing adjacent the open edges thereof for supporting said tube sheet when it has been distorted more than a predetermined amount, and said abutment plate having apertures in alignment with and larger than the tubes connecting through said tube sheet to freely pass the ends of the tubes.
4. In combination in a balanced radiator header, a plurality of heat exchanger tubes disposed in spaced substantially parallel relation, a flexible tube sheet having spaced tube receiving apertures for receiving an end of each of said heat exchanger tubes in hermetically sealed relation, a header casing open on one side, means for securing said header casing to said tube sheet around the peripheral edges thereof, an abutment plate secured inside of said header casing adjacent the open edges thereof for limiting the inward movement of said tube sheet, a port opening from said header casing for transmitting fluid therethrough, an outside cover having spaced apertures passing said tubes in snug sliding relation therethrough and having an offset peripheral flange for spacing it from the outside of said tube sheet for defining a cavity to hold balancing material adjacent thereto, and a gasket of a suitable thickness for insertion between the header casing and the tube sheet to properly space the abutment plate therefrom after said cavity has been packed with balancing material.
5. In combination in a balanced radiator header, a plurality of heat exchanger tubes disposed in spaced substantially parallel relation, a flexible tube sheet having spaced tube receiving apertures for receiving an end of each of said

heat exchanger tubes in hermetically sealed relation, a header casing open on one side, means for securing said header casing to said tube sheet around the peripheral edges thereof, an abutment member secured inside of said header casing for limiting the inward movement of said tube sheet, a port opening from said header casing for transmitting fluid therethrough, an outside cover spaced from the outside of said tube sheet and secured firmly to and around the edges thereof, said outside cover having spaced apertures passing said tubes in snug sliding relation therethrough, a port opening through said outside cover into the space adjacent said tube sheet, and a balancing material packed into said space for supporting the flexible tube sheet in floating relation while permitting the reverse distortions thereof.

6. In combination in a radiator balanced header, a plurality of heat exchanger tubes disposed in spaced substantially parallel relation, a flexible tube sheet having spaced tube receiving apertures for receiving an end of each of said heat exchanger tubes in hermetically sealed relation, a header casing open on one side of substantially dish shaped conformation with a laterally projecting flange for securing said header casing to said tube sheet around the peripheral edges thereof, an abutment member secured inside of said header casing substantially flush with the open edges for limiting the inward movement of said tube sheet, a port opening from said header casing for transmitting fluid therethrough, an outside cover having an offset peripheral flange for spacing it from the outside of said tube sheet and for securing it firmly around the edges thereof, said outside cover having spaced apertures passing said tubes in snug sliding relation therethrough, a port opening through said outside cover into the space adjacent said tube sheet, a balancing material packed into said space for supporting the flexible tube sheet in floating relation while permitting the reverse distortions thereof with substantially free movement, and a gasket insertable between the header casing and the tube sheet for spacing the abutment member therefrom to support said sheet after a predetermined distortion thereof.
